(57) **CLAIM**

The ornamental design for the lip balm spinner, as shown and
described.

DESCRIPTION

FIG. 1 is a side view of the lip balm spinner, an opposing side
view being the mirror image thereof;

FIG. 2 is an end view, taken from the left side of FIG. 1;
FIG. 3 is an end view, taken from the right side of FIG. 1;
FIG. 4 is a perspective view of the lip balm spinner of FIG. 1;
and,

FIG. 5 is another side view of the lip balm spinner.
The broken lines shown in FIG. 5 illustrate the environment
and form no part of the claimed design.
